UNITED STATES PATENT OFFICE.

CHARLES C. TOMKINSON, OF PLAINFIELD, NEW JERSEY, ASSIGNOR TO JOHN EDWARD OGDEN, OF MOUNTAINVILLE, NEW YORK.

BOLT ANCHOR.

Application filed September 10, 1921. Serial No. 499,814.

This invention relates to bolt anchors and more particularly to anchorages such as are used in ceilings for suspending pipe hangers and similar devices.

5 **5** One of the objects of the invention is to provide a shield for anchors constructed in a manner to permit the use of thin walls on the portion of the shield to be positioned in the hole or opening thereby permitting 10 the use of a smaller hole in the wall of building structure.

Another object of the invention is to provide a shield adapted to receive a threaded bolt and having its threaded portion adapted 15 to be positioned outside of the opening in the wall in which the anchor is to be used.

Another object of the invention is to provide a shield having a ceiling plate formed thereon.

20 **20** Another object of the invention is to provide an anchor comprising an expandable shield and means cooperating with the shield for expanding the shield and adapted to exert a radial pressure on all parts of the interior of the expandable portion of the shield.

Another object of the invention is to provide an expansion shield having a portion adapted to be positioned outside the wall opening, said portion having an open throat 30 constructed to permit the driving of the shield into the wall opening without injuring the threads of the shield.

Another object of the invention is to provide a bolt anchor comprising a shield with 35 expandable elements and a filler or expanding element of relatively soft metal constructed and arranged in a manner whereby the expandable elements will be retained against initial expansion before the shield 40 is inserted in the wall opening.

Another object of the invention is to provide a novel method of forming and assembling an expansion shield and the expanding element therefor.

45 **45** The invention may be briefly described as a bolt anchor comprising an expansion shield having a flange acting as a ceiling plate and a threaded portion disposed outside the ceiling plate and further comprises 50 an expanding element adapted to be forced longitudinally in the shield thereby spreading the shield.

One form of the invention involves the

use of a soft metal expanding element or 55 filler adapted to be forced radially in all directions thereby pressing the shield outwardly and being itself forced out between the slots in the shield into engagement with the wall opening.

The invention further includes the method 60 of assembling the shield and expanding element. The shield is longitudinally split or slotted and is cast with the expandable elements spread wide enough apart to permit the entry of the expanding element, the 65 shield thereafter being closed on the element.

In certain forms of the invention the shield has recesses into which the soft metal 70 filler may be forced when the shield and filler are assembled and whereby the expandable parts of the shield are held against any initial or premature expansion before the shield is inserted in the wall opening.

Referring to the drawings, wherein like 75 parts are indicated by like reference characters throughout the several views:

Fig. 1 is a sectional elevation of a bolt anchor constructed in accordance with my invention and shown as expanded in an 80 opening in a wall or ceiling.

Fig. 2 is a sectional elevation of the expansion shield shown in Fig. 1.

Fig. 3 is an elevational view, partly in section, taken at right angles to Fig. 2. 85

Fig. 4 is an end view of the shield shown in Fig. 2.

Fig. 5 is a transverse sectional view taken substantially on line 5—5 of Fig. 2.

Fig. 6 is an end elevation of the inner end 90 of the shield shown in Fig. 2.

Fig. 7 is a transverse sectional view taken substantially on line 7—7 of Fig. 1.

Fig. 8 is a sectional elevation of another form of expansion shield constructed in accordance with my invention. 95

Fig. 9 is an elevational view of the shield shown in Fig. 8, taken substantially at right angles to Fig. 8.

Fig. 10 is a transverse sectional view taken 100 substantially on line 10—10 of Fig. 8.

Fig. 11 is an end elevation of the inner end of the shield shown in Fig. 8.

Fig. 12 is a sectional elevation of another form of shield and expanding means constructed in accordance with my invention. 105

Fig. 13 is a sectional elevation of another form of shield and expanding means constructed in accordance with my invention.

Fig. 14 is a sectional elevation of an expansion shield constructed in accordance with my invention and shown in the form in which it is cast and before the expanding portions are closed on the expanding element.

Fig. 15 is a sectional elevation of another form of shield with a soft metal filler and having means for preventing initial separation of the expandible elements.

Figs. 16 and 17 are sectional elevations taken substantially on lines 16-16 and 17-17 of Fig. 15.

Fig. 18 is a sectional elevation of still another form of shield similar to that shown in Fig. 15.

Figs. 19 and 20 are sectional elevations taken substantially on lines 19-19 and 20-20 of Fig. 18.

Fig. 21 is a sectional elevation of the shield shown in Figs. 1 and 2 but with another form of soft metal filler, and

Fig. 22 is a sectional elevation of the shield shown in Figs. 1 and 2 but with still another form of filler.

The bolt anchor about to be described is particularly adapted for use in ceilings for supporting pipe hangers and in Fig. 1, I have shown a portion 20 of a wall or ceiling and an expansion shield 21 expanded into the opening 22 in the wall 20.

The expansion shield is preferably formed from a malleable iron casting and is provided with a plurality of longitudinal slots 23 extending inwardly from the inner end 24 of the shield. The slots 23 divide the shield into a plurality of expandible elements 25, and the inner ends of these elements have formed thereon ribs 26 adapted to engage the wall opening, the ribs being connected by webs 27.

The inner surfaces of the expandible elements converge toward the inner end of the shield as shown at 28.

The shield has formed integral therewith a laterally extending flange 29 which forms a ceiling plate and the shield also has formed integral therewith a sleeve portion 30 extending outwardly or beyond the plate 29. From the showing, particularly in Fig. 2, it will be noted that the wall of the portion 30 is much thicker than the wall of the remaining portion of the shield since the wall 30 is screw threaded to receive a bolt 31. By making the wall of the inner portion of the shield thinner a smaller opening or hole in the wall 20 may be used, thereby making a decided saving in the labor cost of drilling these holes. As shown also in Fig. 2 the outer end of the opening in the portion 30 of the shield is beveled as indicated at 32 forming an open throat and this

construction permits the driving of the shield into the wall opening without injury to the screw threads and facilitates the insertion of the bolt 31.

In order to prevent the shield from turning in the opening and also to assist in retaining the shield in place before the rods or bolts are inserted, a plurality of lugs or fins 33 is provided, these fins being located adjacent the flange 29 and extending longitudinally of the shield.

In the form of the invention illustrated in Figs. 1-7 inclusive, a soft metal expanding element 34 is used, this element being positioned within the shield in a manner hereinafter set forth and substantially conforming in shape to the inner surface of the end portion of the shield. This soft metal element 34 also has laterally extending webs 34' that are received by the slots 23 and the outer edges of webs 34' are substantially flush with the outer wall of the shield. It should be understood, however, that this particular shape is not essential and any form of soft metal filler may be utilized

equally well. In Fig. 2 the expanding element and expansion shield are shown before expansion by the rod or bolt 31. In Fig. 1, however, the rod is shown in expanding position and the soft metal of the filler 34 has been forced longitudinally of the shield as shown at 35 and has also been forced outwardly between the slots as shown in Fig. 1 at 36 and in Fig. 7 at 37. The portion 37 of the soft metal engages the wall of the opening and assists in retaining the anchor in position. When the bolt 31 has been forced into the member 34 the soft metal is forced laterally and exerts a radial pressure on all portions of the shield with which it contacts thereby spreading the expandible shield parts 25 and passing through the slots as above explained. The spreading of the expansion elements forces the shield and particularly the ribs 26 into firm engagement with the wall of the opening and forces the soft metal also into contact with the wall thereby firmly retaining the anchor in position.

In Figs. 8-11, inclusive, another form of expansion shield is shown, this shield having four expandible portions 40 formed by four longitudinal slots 41 whereas the structure shown in the preceding figures contained only a pair of expansion elements and a pair of slots.

In Fig. 12 a similar shield is shown but in this form no expanding element other than the rod or bolt 21 is used. The end of this bolt contacts directly with the converging portions of the expandible parts of the shield.

In Fig. 13 the shield illustrated is similar to that shown in Figs. 8-11 but in this form of the invention an expanding element 42 of

hard metal is utilized. As the bolt or rod travels inwardly in the shield shown in Fig. 13 the end of the bolt will engage the element 42 and will force this member longitudinally in the shield thereby spreading the expandible elements 40.

In Fig. 14 I have illustrated the method of assembling the anchor above described. The shield is shown in the form in which it is cast with the expandible elements 25 expanded sufficiently to permit the insertion of the expanding element 34. After this element has been inserted the expandible portions 25 of the shield are compressed or forced inwardly closing on the expanding element as shown in Figs. 2 and 3. The parts are then ready for insertion in the wall opening.

Instead of using a pre-formed expanding element or filler such as shown in Fig. 14 and in preceding figures, other forms of expanding elements may be used.

In Figs. 16-20 the anchor is formed by casting or otherwise forming the shield with the expandible elements spread apart as shown in Fig. 14 and by closing these elements on an expanding element of cylindrical or other preferred shape.

As the expandible elements are forced down on the soft metal element the latter is squeezed into the shape of the interior of the bore of the shield and outwardly through any openings in the wall of the shield.

In order to retain the shield expandible elements and to counteract any premature expanding of the elements when the pressure used to close them on the expanding element, is removed, I have shown in Figs. 15-20 means in the form of depressions or recesses or apertures in the inner wall of the shield.

In Figs. 15 and 16 dovetail openings 43 are shown in the shield and also cylindrical or straight openings 44 are shown in Figs. 15 and 17. Either of these forms of opening will have the effect of bonding the expandible elements against separation or premature expansion.

In Figs. 18-20 the shield is shown as provided with longitudinal dovetail grooves 45 on the inner wall and the forcing of the soft metal into these grooves bonds the expandible parts together.

In Fig. 21 is shown an expanding element 46, of a form to be inserted through the threaded opening of the shield. This element may be cylindrical or of any other desired shape and upon the longitudinal movement of the bolt in the shield the element 46 will be compressed and will expand the expandible elements of the shield and be forced outwardly as in the construction shown in preceding figures and already described.

In Fig. 22 is shown an expanding element 47 adapted to enter the shield through the threaded opening and having its outer surface conical in shape or tapered to conform to the interior of the shield.

From the above description it will be seen that a shield has been provided having one portion of its wall relatively thick to receive screw threads and having another portion adapted to be positioned in an opening in a wall provided with relatively thin walls thereby permitting its use in openings of smaller diameter than would otherwise be possible. The shield also has formed integral therewith a flange or ceiling plate. The expanding element, moreover, is adapted to be forced inwardly thereby spreading the expandible portions of the shield, and in the case of the soft metal element, exerting a radial, outward pressure on the shield and being forced outwardly through the openings in the shield into engagement with the wall opening, thereby forming an exceedingly strong anchorage.

Although certain specific embodiments of the invention have been illustrated and described, it will be understood that the invention is capable of further modification and that changes in the construction and in the arrangement of the various cooperating parts may be made without departing from the spirit or scope of the invention as expressed in the following claims.

What I claim is:

1. In combination, an expansion shield of relatively hard metal having a plurality of expandible elements and having a threaded portion for receiving an expanding element and a soft metal mass positioned within said elements and adapted to spread the elements.

2. In combination, a one piece expansion shield of relatively hard metal having a plurality of expandible elements, a flange intermediate the ends of the shield and a threaded portion extending beyond the flange and means including a mass of soft metal disposed within the shield for engaging and expanding the expandible elements.

3. In combination, an expansion shield having an expandible portion adapted to be received and expanded within an opening in a wall and a portion having threads adapted to be positioned outside the hole and a soft metal expanding element disposed within the expandible portion of the shield consisting of a mass of metal extending substantially across the bore of the opening in said expandible portion.

4. In combination, an expansion shield having an expandible portion adapted to be received and expanded within an opening in a wall, a portion having threads adapted to be positioned outside the hole, a flange be-

tween said portions and a soft metal expanding element disposed within the expandable portion of the shield consisting of a mass of metal extending substantially across the bore 5 of the opening in said expandable portion.

5. A bolt anchor comprising an expansion shield having an open end and expandable elements and an expanding element of relatively soft metal adapted to be inserted 10 through the open end of the shield and to be positioned within the shield.

6. A bolt anchor comprising an expansion shield having an open end and expandable elements and a cylindrical expanding element 15 of relatively soft metal adapted to be inserted through the open end of the shield and to be positioned within the shield.

7. A bolt anchor comprising an expansion shield having an open end and expandable 20 elements and an expanding element of relatively soft metal adapted to be inserted through the open end of the shield and to be positioned within the shield, said expanding element being shorter in length than the 25 shield.

8. A bolt anchor comprising an expansion shield having expandable elements and having a threaded opening in one end adapted to receive a threaded member, an expanding 30 element having a cross section smaller than the opening and adapted to be inserted in the shield through the opening and means engaging the threaded opening of the shield and engageable with the expanding element 35 to cause said element to expand the shield.

9. A new article of manufacture comprising an expansion bolt having a hollow perforated portion adapted to extend into a hole and another portion adapted to extend on 40 the exterior of the hole to cover and conceal the hole and adapted to support a bolt or screw, and compressible material mounted within the hollow perforated portion, and adapted to be forced radially through perforations to make a bond or grip with a wall or other suitable support.

10. A new article of manufacture comprising an expansion bolt having a hollow perforated portion, the outer end of the expansion bolt being provided with a flange, head 50 or rosette to extend out of a hole and conceal it, compressible material mounted in the hollow perforated portion, means to engage

on the end of said compressible material and force portions of it out through the perforations in the hollow expansion bolt. 55

11. A new article of manufacture comprising an expansion bolt having a hollow perforated portion, the outer end of the expansion bolt being provided with a flange, head or 60 rosette to extend out of a hole and conceal it, compressible material mounted in the hollow perforated portion, means engageable with the end of said compressible material to force portions of it out through the perforations in 65 the hollow expansion bolt.

12. A new article of manufacture comprising an expansion bolt having a hollow perforated portion, the outer end of the expansion bolt being provided with a flange, head or 70 rosette to extend out of a hole and conceal it, compressible material mounted in the hollow perforated portion, means engageable with the end of said compressible material to force portions of it out through the perforations in 75 the hollow expansion bolt and a bolt or screw to cooperate with the flange, head or rosette.

13. A bolt anchor comprising an expansion shield having lateral openings therein and having a ceiling plate formed on its outer 80 end portion, compressible material of relatively soft metal disposed within said shield and means for forcing said compressible material through said lateral openings to anchor the shield. 85

14. A bolt anchor comprising an expansion shield having tapered walls and lateral openings therein, and having a ceiling plate formed on its outer end portion, compressible material of relatively soft metal disposed within said shield and means for forcing said compressible material through said lateral openings to anchor the shield. 90

15. A bolt anchor comprising an expansion shield having a bore constricted at its 95 inner end and having lateral openings therein, said shield having a ceiling plate formed on its outer end portion, compressible material of relatively soft metal disposed within said shield and means for forcing said compressible material through said lateral openings to anchor the shield. 100

In witness whereof, I have hereunto set my hand this 3rd day of August, 1921.

CHARLES C. TOMKINSON.
